ATTORNEY

UNITED STATES PATENT OFFICE.

JOHN E. FREY, OF NEW YORK, N. Y., ASSIGNOR TO GRINDEN ART METAL COMPANY, A CORPORATION OF NEW YORK.

METALLIC STRUCTURE, SUCH AS DOORS AND THE LIKE.

1,018,896.

Specification of Letters Patent.

Patented Feb. 27, 1912.

Application filed August 3, 1910. Serial No. 575,249.

To all whom it may concern:

Be it known that I, JOHN E. FREY, a citizen of the United States, and a resident of the borough of Brooklyn, county of Kings, 5 city and State of New York, have invented certain new and useful Improvements in Metallic Structures, Such as Doors and the Like, of which the following is a full, clear, and exact description, reference being had 10 to the accompanying drawings, forming part of this specification.

This invention relates to metallic structures, such as doors, paneling, wainscoting, partitions, frames and windows, and the object thereof is the production of a sheet metal structure which can be economically manufactured and which shall be light and strong.

Further objects of the invention will be 20 hereinafter referred to in the detailed description of the invention.

For descriptive purposes, I have illustrated and will describe a metallic door embodying my invention, but it is to be understood that, except as specifically pointed out, the invention as to details is susceptible of modification without departing from the spirit of the invention, and that it is 25 equally applicable to structures other than doors.

Figure 1 of the drawings is an elevation of a door embodying the invention; Fig. 2 is a vertical section on a larger scale on the line 2—2 (Fig. 1); Fig. 3 is a sectional assembly view of the parts shown in Fig. 2; Fig. 4 is a sectional view on the line 4—4 (Fig. 1); Fig. 5 is an assembly view thereof and Fig. 6 is a sectional view of a modified construction.

Similar reference characters are employed to designate corresponding parts in all the views.

The structure illustrated comprises stiles 1 and 2 and top, bottom and lock rails 3, 4 and 5 which I have herein referred to as frame members. Within the frame members are mounted panels 7 and 8. The frame members in the structure illustrated are formed with oppositely placed walls 10 and 11, and are provided with interlocking slots and flanges or tongues, the slots being formed on either the end members or rails or on the side members or stiles. The slots are formed by bending the interior margins 50 or edges of the member back so as to leave

an open slot 12, and then bending or recurving the metal to form another substantially parallel slot 14. The flanges or tongues 15 are formed on the edges of the walls of the other members and enter and fit tightly 60 the slots 14; they are preferably offset so that the faces of the members will be in the same plane. In the structure illustrated the slots are formed on the stiles and the flanges are formed on the rails.

A stay member 17 is provided, which in the structure shown is formed with upturned flanges 19 which enter and fit tightly 65 the slots 12, thus rigidly supporting the walls of the structure.

The panel members 7 and 8 of the structure are provided with flanges 20, which enter and fit tightly the slots 14. The flanges 20 may be formed integrally with the panels, or they may be formed on molding strips 21, which are properly connected with the panels, as for instance in the manner shown in Fig. 6. In this view the space between the panels is filled with some non-conducting material, such as asbestos or 70 mineral wool 22.

When properly assembled the different members are permanently secured together, preferably by electric welding.

I claim:

1. A metallic structure of the character described, having interconnected members, one of said members being formed with two substantially parallel slots, another of said members being provided with a flange which 90 extends into one of said slots, and a stay member provided with a flange which extends into the other of said slots.

2. A metallic structure of the character described, comprising members having oppositely disposed walls bent adjacent to their edges to form two substantially parallel slots, members each connected with said slotted members by means of a flange projecting into one of said slots, and a stay member between the walls of the slotted members provided with flanges which enter the other slots.

3. A metallic structure of the character described, comprising a frame having side 105 and end members with oppositely disposed walls having their interior edges bent to form two substantially parallel slots, stay members between the walls of the frame members having flanges projecting into the 110

slots in the frame members, and a panel member connected with the frame members by flanges projecting into the other slots.

4. In a metal door, metal stiles, stiffening members therefor, panels, molding for said panels, and rails, said stiles, rails and stiffening members having interlocking flanges.

5. In a metal door, metal stiles and metal rails forming sheet metal boxes, one of said boxes being open at one edge, and a strip covering this otherwise open edge, one of said boxes being formed with two pairs of slots, the other box having flanges entering one pair of the slots and the strip having flanges to enter the other pair of slots.

6. A metallic structure of the character described, having interconnected members, one of said members being formed with two

pairs of slots, another of said members being provided with flanges each of which extends into one of said slots, and a stay member provided with flanges which extend into the others of said slots.

7. In a metal door, metal stiles and metal rails forming sheet metal boxes, one of said boxes being open at one edge, and a strip covering this otherwise open edge, one of said boxes having its edges bent to form two pairs of slots, the other box having flanges entering one pair of the slots and the strip having flanges to enter the other pair of slots.

JOHN E. FREY.
